(57) **CLAIM**

The ornamental design for a greeting card album, as shown and described.

DESCRIPTION

FIG. 1 is a top plan view of a greeting card album fully open; FIG. 2 is a front angle perspective view of the greeting card album one-quarter open;

FIG. 3 is a rear angle perspective view of the greeting card album one-quarter open;

FIG. 4 is a rear angle perspective view of the greeting card album fully closed; and,

FIG. 5 is a front angle perspective view of a page insert of the greeting card album shown separately for convenience of illustration.

The broken lines showing environment in the drawings are for information purposes only and form no part of the claimed design.
